UNITED STATES PATENT OFFICE.

GEORGE K. BRAYMEN, OF EAST WENONA, ILLINOIS.

COMBINATION GRIPPER, PERFORATING, AND SCORING ATTACHMENT FOR PRINTING PRESSES.

Application filed August 2, 1920. Serial No. 400,645.

To all whom it may concern:

Be it known that I, GEORGE K. BRAYMEN, a citizen of the United States, residing at East Wenona, in the county of La Salle and 5 State of Illinois, have invented new and useful Improvements in Combination Gripper, Perforating, and Scoring Attachments for Printing Presses, of which the following is a full, clear, concise, and exact description, 10 reference being had to the accompanying drawing, forming a part of this specification.

This invention relates to a combination gripper and perforating or scoring attachment for printing presses, and more particularly to a device of this character adapted for simultaneous upright and cross-perforations and the like which are accomplished in the press at the same time that the printing is being performed. Devices adapted 15 for simultaneous printing and upright scoring are old in the art, but when these devices are to be utilized on blanks which it is desired to cross-score or perforate, it is necessary to run the blanks through the press a second time for the cross-scoring, 20 which operation is known in the trade as a "double run."

One of the objects of this invention, therefore, resides in the production of an improved device in which the printing and upright and cross-scoring and the like can be performed in one operation, so as to eliminate the so-called double run.

35 The invention comprises an improvement on the combination gripper and scoring device illustrated and described in the United States Patent to G. H. Cole, No. 1,270,788, issued July 2nd, 1918, and comprises additions and modifications to the apparatus described in said patent whereby the desired upright and cross-scoring can be performed in one operation.

Another object of the invention comprises 45 the production of an improved device of this character which produces upright and cross-scoring, which meet at a substantial right angle corner and in which the cross-scoring does not extend beyond the line of the upright scoring, an evil which is prevalent when cross-scoring is obtained by means of the so-called double run. The extension of the cross-scoring beyond the line of the upright score is frequently very objectionable, this being especially so in the printing

and scoring of sheets with which stubs are used, such as check books and the like, because the cross-score is not desired on the stub.

A further object of the invention resides 60 in the production of an improved form of apparatus of this character with which the cross-scoring attachment can be adjusted to any desired position with respect to the upright score.

A still further object comprises the production of an apparatus capable of carrying a plurality of cross-scores, each of which is adjustable with respect to the upright score and with respect to one another.

Other objects of the invention will become apparent from the following description, the accompanying drawings, and the appended claims.

For the purposes of description, the preferred embodiment of the invention is illustrated in the accompanying drawings, in which—

Fig. 1 is a view in front elevation of the upright combination gripper and perforator 80 fitted with two cross-perforators;

Fig. 2 is a view of a portion of the cross-gripper, partly in section, taken on the plane indicated by the line 2—2 of Fig. 1, looking in the direction of the arrows;

Fig. 3 is a vertical section of one end of the cross-gripper taken on the plane indicated by the line 3—3 of Fig. 1, looking in the direction of the arrows;

Fig. 4 is a side elevation, partly in section, of the combination vertical gripper and scoring attachment;

Figs. 5, 6 and 7 are side views of interchangeable blades for use in connection with the scoring or perforating attachments;

Fig. 8 is a vertical section of the cross-scoring and perforating attachment taken on the plane represented by line 8—8 of Fig. 2, looking in the direction of the arrows;

Fig. 9 is a blank which illustrates the character of scoring which may be obtained, together with the printing, in one operation of the press.

Referring to the drawings, the upright 105 combination gripper and scoring attachment consists of the mounting element or base 10 which carries at either end the springs 11 and 12 respectively, which springs co-operate with the blade-carrier 13 whereby 110

the blade 14 is normally held in position in the slot 15 of the base 10, so that the cutting edge of the blade is entirely enclosed within said slot. The blade-carrier 13 is equipped 5 at either end with a countersunk hole such as 16, said hole carrying a screw 17 which is threaded into the base 10. The head of the screw 17 is loosely fitted in the countersunk portion of the hole 16, the head of the 10 screw serving to limit the upward movement of the blade-carrier 13 under the action of the springs 11 and 12. Thus, when the blade-carrier 13 is moved to the extreme 15 position under the influence of the springs 11 and 12, in which position the head of the screw 17 contacts with the lower portion of the countersunk part of the hole 16, the blade 14, positioned in the blade-carrier 13, will be completely enclosed within the slot 20 15 of the mounting-base 10.

The blade 14 may be secured to the blade-carrier by any suitable means, but, in the preferred construction illustrated in the drawings, this is accomplished by a screw 25 such as 18 fitted into the blade-carrier at either end thereof. The screw 18 is flat headed and the head of the screw contacts with slots such as 19 cut in either end of the blade 14, the head of the screw and the 30 slot 19 cooperating to securely hold the blade 14 in a slot 20 cut in the blade-carrier to receive the top portion of the blade.

The upper face 21 of the blade-carrier 13 is milled out at one edge thereof for the 35 purpose of obtaining a flat face portion 22 below the upper face 21 of the remaining portion of the blade-carrier 13. The purpose and function of this depressed face 22 will be explained hereinafter.

40 Adjacent the edge of the blade-carrier 13, which is fitted with the depressed face 22, is a groove or slot 23 which extends for substantially the entire length of the blade-carrier and which is fitted at the upper end 45 with a cut away portion 24. This groove or slot 23, together with the depressed face 22 on the top of the blade-carrier, functions to connect the end of the cross-perforator with the upright gripper or perforator. 50 This interconnection between the cross-perforator and the upright perforator is clearly illustrated in Fig. 2.

As illustrated in Fig. 2, the end of the blade-carrier 25 of the cross-perforator is 55 formed to produce a hook portion 26, the forwardly upwardly extending part 27 of said hook portion snugly fitting in the groove 23 of the upright blade-carrier. The top face of the cross-blade-carrier 25 is cut 60 away at the hook end to receive a flat spring 27, which projects over the end of the cross-blade-carrier and onto the depressed portion 22 of the upright blade-carrier. The spring 27 is secured to the cross-blade-carrier 65 by any means, preferably by rivets such as

28. As illustrated in Fig. 1, these rivets secure the spring 27 to the cross-blade-carrier 25 at substantially the extreme inner end so as to give the projecting end of the spring 27 the desired amount of resilience, 70 whereby said spring will function to tightly hold the hook portion 26 of the cross-perforating blade-carrier in the groove 23 of the upright perforating blade-carrier. The cross-blade-carrier is fitted with a slot 29 to 75 receive the cross-perforating blade 30, the blade being secured to the carrier 25 by screws such as 31 in a manner identical to that described in connection with the blade securing means for the upright perforator. 80

The vertical movement of the cross-blade-carrier, whereby the cutting edge of the blade 30 is confined within a slot 32 of a mounting base 33 of the cross-perforating mechanism, is secured by springs such as 85 34 and the spring 35, together with the limiting screws such as 36. The limiting screws 36' are secured in the mounting base and fitted in countersunk holes in the blade-carrier 25 in a manner identical to that described for the same mechanism in connection with the upright perforator. The spring 35 secured to one end of the base 33 (see Fig. 3), and adapted to maintain one end of the blade-carrier 25 in its normally raised 90 position is secured to the base 33 in any manner, preferably by rivets. The springs 34, which function to maintain the other end of the cross-blade-carrier 25 in its normally raised position, are fitted in slots 36 100 positioned in the side of the blade-carrier 25 and are secured in this position preferably by means of rivets. These springs 34 have a forwardly and downwardly extending portion 37 which contacts with the base 105 portion 33, the springs normally being in compression so as to maintain this end of the blade-carrier 25 in the extreme raised position against the heads of the screws 36'. A spring such as 34 is secured to the cross-blade-carrier in the same position on either side of the blade 30. 110

115 The base portion 33 carries a countersunk surface 38 over which is positioned a plate 39 which is fitted with a like countersunk surface 40, the two countersunk surfaces combining to form a slot adapted to receive the arm 41 of a gripper 42. The slot formed by the countersunk portions 38 and 40 of the base 33 and plate 39 respectively is designed so that one edge thereof is slightly tapered to receive the tapered side 43 of the gripper 42. The gripper 42 and the base 10 are each equipped with perforations such as 44 by means of which they are 120 adapted to be mounted on suitable mechanism of the press by any means well known to those skilled in the art. 125

130 The base plate 33 of the cross-perforating mechanism is slotted for substantially the

entire length of the blade, and as illustrated in Fig. 8, the one end of this base plate is fitted with a pin 46 which serves to hold the two arms of this base plate in alignment, the cross-perforating blade 30 being suitably slotted so that the blade will readily ride over the pin 46.

Figs. 5, 6 and 7 show blades which can be interchangeably connected to the blade-carriers, the blade 14 of Fig. 6 showing a perforating blade in which the perforations extend for the entire length of the blade.

Fig. 5 shows a blade 47 which has perforations for only a portion of its length, and Fig. 7 shows a blade 48 used for either cutting or scoring.

In this specification, whenever any of the terms "cutting," "scoring" or "perforating" are used to describe the means utilized for 20 making the impression upon the paper upon which the printing is being performed, it is to be understood that these terms are used synonymously; that is, that the blades can be readily interchanged, and that the apparatus is equally well adapted to perform either perforating, scoring or cutting operations.

It will be understood that in the operation of the press to which the apparatus 30 herein described is to be applied, that the successive actions of the platen of the press serve to depress the upright and cross-blade-carriers and force the operating or cutting edges of the blades into or through 35 the paper or cardboard on which the printing and scoring or cutting operation is being performed.

It will likewise be understood that the blades can be readily interchanged by removing screws such as 18 whereby the apparatus can be adapted to suit the prospective work which it may be desired to accomplish.

In assembling the apparatus on the press 45 the perforations 44 in the base 10 of the combination gripper and perforating attachment and in the gripper 42 are secured to suitable means associated with the press in a manner well known to those skilled in the 50 art.

When the gripper 42 and the combination gripper and perforating attachment have been thus secured to the press, the arm 41 of the gripper 42 is pushed through 55 the slot formed by the countersunk portions 38 and 43 in the cross-perforator-bar. The cross-perforator-bar is then slid down on the arm 41 until the other end of the cross-gripper-bar reaches the opening 24 in the 60 upright combination gripper and perforator. When the other end of the cross-perforator-bar is opposite this opening 24, the end of the cross-perforator-bar is inserted through said opening 24 into the 65 groove 23, and the cross-perforator-bar is

then pushed down on the arm 41 of the gripper and on the upright combination gripper and perforator. In this further movement the hook portion 26 of the cross-perforator-bar will ride in the groove 23 70 of the upright gripper and the spring 27 will solidly hold this end of the cross-gripper-bar in its position and connection with the upright gripper. The end of the spring 27 will rest in the depressed face 75 22 whereby the top face of the cross-perforator and the top face of the upright perforator will all rest in substantially the same plane and represent a flush surface. The cross-gripper-bar is now pushed down 80 on the gripper 42 and the combination gripper and upright perforator until the desired location has been reached. When this position is attained, the cross-perforator is positively positioned by means of screws 85 such as 48 which serve to draw the plate 39 into close contact with the mounting base 33 of the cross-perforator whereby the upright arm 41 of the gripper 42 will be rigidly clamped in the countersunk portions 90 38 and 43 which form the slot in which this upright arm 41 is positioned.

This clamping action between the plate 39 and the mounting bar 33 serves to positively position the cross-perforator and prevents 95 any movement thereof when it is acted upon by the platen of the press in the act of perforation. If a plurality of cross-perforators are desired, these are secured to the gripper 42 and to the combination 100 gripper and upright perforator in a manner identical to that which has just been described. These additional cross-perforators are positively positioned in the desired place by the same clamping action, and, 105 consequently it will be evident that with an apparatus constructed in accordance with the teachings of this invention any number of cross-perforators may be used which may be adjusted and positioned as 110 desired, so as to obtain any character of cross perforation.

Fig. 9 illustrates one character of blank which may be obtained with the combination upright and cross-perforating apparatus constructed in accordance with the teachings of this invention. It will be observed that in this blank the upright perforation 50 is met by the two cross-perforations 51 and 52 at substantially right angles 115 at 53 and 54 respectively, and that the cross-perforators do not extend over into the stubs 55. A sharp right angular relationship between the upright and cross-perforators such as illustrated at 53 and 54 on 120 the blank are obtained with this apparatus because the upright blade 14 meets the cross-blade 30 at substantially right angles and in substantially close contact, as clearly 125 understood in Fig. 2.

It will now be evident that with the apparatus described in this application it is possible to obtain printing and simultaneous upright and cross-perforation for each operation of the platen of the press, and that the perforating apparatus can be adjusted so that any desired number of cross-perforations can be obtained with the upright perforation. Also, that the cross-perforations meet the upright perforations at substantially right angles and that the cross-perforations do not extend beyond the upright perforations, thereby eliminating the detrimental feature of extending the cross-perforation onto the stubs which cannot be avoided in the double run and which is very unsatisfactory.

The invention is obviously not limited to the specific embodiment thereof herein illustrated and described, but is capable of many modifications and alterations within the spirit and scope of the invention as set out in the appended claims.

What I claim as new and desire to secure by Letters Patent of the United States is:

1. In a device of the character described, in combination, an upright scoring and gripper means, a cross-scoring means, spring-actuated means to secure said cross-scoring to said upright scoring means, and means actuated by the platen of the press to operate said upright and said cross-scoring means whereby upright and cross-scoring is obtained simultaneously with the printing operation.

2. In a device of the character described, in combination, an upright and cross-scoring means adjustably secured to one another, scoring-blades carried by each said upright and cross-scoring means, a gripper, means to adjustably secure one end of the cross-scoring means to said gripper, spring actuated means to adjustably secure the other end of said cross-scoring means to said upright scoring means, and means adapted to be operated by the press platen whereby simultaneous printing and cross and upright scoring is obtained.

3. In a device of the character described, in combination, an upright scoring means, a cross-scoring means, scoring-blades carried by each said means, spring actuated means to attach said cross-scoring means to said upright scoring means whereby said blades will meet at substantially right angles, and means adapted to operate said blade under press platen pressure whereby simultaneous cross and upright scoring is obtained.

4. In a device of the character described, in combination, an upright scoring means, a plurality of cross-scoring means, scoring blades carried by each said means, spring actuated means to attach said cross-scoring means to said upright scoring means, and means adapted to operate said upright scor-

ing means and said plurality of cross-scoring means under platen pressure whereby simultaneous cross and upright scoring is obtained.

5. In a device of the character described, in combination, an upright scoring means, a plurality of cross-scoring means, scoring-blades carried by each said means, spring actuated means to adjustably attach said plurality of said cross-scoring means to said upright scoring means whereby the blades of said cross-scoring means will meet the blade of said upright scoring means at substantially right angles, a gripper, means to adjustably secure one end of said plurality of cross-scoring means to said gripper, and means adapted to operate the blades of said upright scoring means and said plurality of cross-scoring means under press platen pressure whereby simultaneous cross and upright scoring is obtained.

6. In a device of the character described, in combination, a combined gripper and upright scoring means, a cross-scoring means, spring actuated means comprising a hook and slot connection for adjustably securing said cross-scoring means to said upright scoring means, a gripper, means to adjustably secure said cross-scoring means to said gripper, said last mentioned means being adapted to rigidly position the cross-scoring means in any one of a desired plurality of scoring positions, and means carried by both the upright and cross-scoring means whereby simultaneous upright and cross-scoring is obtained through press platen pressure.

7. In a device of the character described, in combination, a combined gripper and upright scoring means, a longitudinal slot positioned in the side of said upright scoring means, a plurality of cross-scoring means, spring-actuated means associated with one end of said cross-scoring means to adjustably position said plurality of cross-scoring means in said slot, a gripper, and means to adjustably secure the other end of said cross-scoring means to said gripper.

8. In a device of the character described, in combination, a combined gripper and upright scoring means, a plurality of cross-scoring means, spring actuated means to adjustably secure one end of said cross-scoring means to said combined gripper and upright scoring means, a gripper, and means to adjustably secure the other end of said cross-scoring means to said gripper.

9. In a device of the character described, in combination, a combined gripper and upright scoring means, a plurality of cross-scoring means, spring actuated means to adjustably secure one end of said cross-scoring means to said combined gripper and upright scoring means, a gripper, means to adjustably secure the other end of said cross-scoring means to said gripper, and means as-

sociated with said last mentioned means to positively position the cross-scoring means in any one of a desired plurality of positions.

10. In a device of the character described, in combination, a combined upright scoring and gripper means, a cross-scoring means, a scoring-blade associated with each said means, spring actuated means operated to normally maintain the blades in the non-
10 actuating position, means to adjustably secure one end of said cross-scoring means to said combined upright scoring and gripping

means, a gripper, means to adjustably secure the other end of said cross-scoring means to said gripper, and means actuated by the 15 platen of the press to compress said springs to obtain a simultaneous upright and cross-score.

In witness whereof, I have hereunto subscribed my name.

GEORGE K. BRAYMEN.
